C. R. HARVEY.
AIR HEATING FURNACE.

No. 10,447.

PATENTED JAN. 24, 1854.

TAKEN FROM PATENT OFFICE REPORT
1854 - VOL. II -
ONLY DRAWING ACCESSIBLE (1913)

UNITED STATES PATENT OFFICE.

CHARLES R. HARVEY, OF NEW YORK, N. Y.

AIR-HEATING FURNACE.

Specification of Letters Patent No. 10,447, dated January 24, 1854.

To all whom it may concern:

Be it known that I, CHARLES R. HARVEY, of the city and county of New York and State of New York, have invented a new and Improved Air-Heating Furnace for Warming Dwellings, Stores, Churches, School-Houses, &c.; and I do hereby declare that the following is a full and exact description thereof, reference being had to the drawings that will accompany this specification.

My improvements consist, first, in the mode of constructing and arranging the top of the fire chamber, by which an equal expansion of all its parts are effective, and the gases are made to reverberate and consume, the draft flue being projected down into the center of the chamber, so that an equal reverberatory action takes place from all sides to the exit pipe at the center, thus attaining all the advantages of a diving flue, without the inconvenience from unequal attraction of the currents of heat, &c., to one side, and the irregular expansion and contraction attendant thereon. By means of this construction the flame and heat of the fire are allowed to ascend, and are then compelled to reverberate in the top or dome B, whence they descend and pass off at the center, a plan that I have found to consume the gases more perfectly, and give out their heat more entirely than in any other way, an effect which has been only partly attained heretofore.

The arrangement of the radiating pipes are of diamond form in connection with the ash pan below, by which the ashes can be entirely cleared out from the radiating pipes D; the general features of which are not new, or claimed by me; this radiating pipe

D is so arranged, that when the damper (a) ⁴⁰ is shut, the smoke and heat is compelled to pass around the circuitous turns in the winding pipe through the air chamber within which it is coiled. This part of the pipe is constructed with elbows turning at nearly ⁴⁵ right angles, by which the heat is more fully absorbed, and the radiating power thus more entirely exhausted. The lower angles of this radiating pipe D, are each connected with a long horizontal soot chamber C, when ⁵⁰ the lattice valve is open; this valve, however, is generally closed, and is always so when the furnace is in action; but when the pipes are to be cleaned, the valve is drawn back, opening the division between each of ⁵⁵ the pipes D, and the soot box; and then by beating upon the pipes all the soot, &c., is made to fall into the soot box C, below, from whence it is easily removed without in any way disturbing the pipes D; around the soot ⁶⁰ chamber is a recess E, forming an evaporating pan.

Having thus fully described my improvement in the air-heating furnace, I wish it to be understood that I do not claim a diving ⁶⁵ flue, or a coil of heating pipe, as they are both well known devices: but

What I do claim as my invention, is—

Constructing the bonnet or top of the fire chamber, with a depression at the center, into which the smoke or exit pipe enters, ⁷⁰ so that the heat is equalized all around, and the expansion and contraction is made uniform, as above specified.

C. R. HARVEY.
